UNITED STATES PATENT OFFICE.

CHARLIE EDWIN WEEKS, OF OAKLAND, CALIFORNIA, ASSIGNOR OF ONE-THIRD TO ERNEST J. COOK, OF OAKLAND, CALIFORNIA, AND ONE-THIRD TO HAGER LEON, OF SAN FRANCISCO, CALIFORNIA.

PAPER-ROLL ABUTTER.

1,094,765.

Specification of Letters Patent. Patented Apr. 28, 1914.

Application filed October 20, 1913. Serial No. 796,215.

To all whom it may concern:

Be it known that I, CHARLIE EDWIN WEEKS, a citizen of the United States, residing at Oakland, in the county of Alameda 5 and State of California, have invented new and useful Improvements in Paper-Roll Abutters, of which the following is a specification.

This invention relates to improvements in 10 holders for rolls of paper such as are used for wrapping paper, toilet paper and the like.

The object of the invention is to provide 15 an attachment for paper roll holders for automatically projecting the end of the roll of paper after the desired amount has been torn off to provide for the ready gripping of the paper by one end when another supply is required.

20 With this and other objects in view, the invention consists of certain novel features of construction, and the combination and arrangement of parts as will be more fully described and claimed.

25 In the accompanying drawings: Figure 1 is an end elevation of a roll holder equipped with this attachment and with the attachment in raised position. Fig. 2 is a similar view with parts broken out and with 30 the attachment in lowered position which it assumes when the paper is being unwound from the roll. Fig. 3 is a front elevation thereof. Fig. 4 is a transverse section thereof. Fig. 5 is a detail plan view of one end 35 of the feeding rolls. Fig. 6 is a detail view of one of the rollers.

This attachment may be applied to any 40 roll holder and in the embodiment illustrated is shown mounted on a stand comprising a base A having spaced uprights B and C connected at their upper ends by a cross bar D. A shaft E is revolvably mounted in the uprights B and C and on which a paper web F is wound. This improved attachment 45 as shown comprises a frame composed of two arms 1 and 2 pivotally mounted at one end on studs 3 which project from the outer face of the uprights B and C, preferably below the shaft E. The other ends of these 50 arms 1 and 2 are connected by a paper feeding and severing device in the form of upper jaws 4 and lower jaws 5 hingedly connected at one end as shown in Fig. 3 to provide for the placing of the paper web as is

shown clearly in Fig. 2. These jaws have 55 longitudinally extending upper and lower cutting blades 4' and 5' for severing the paper web at this point, the upper blade being shown hollow ground and the lower ground at right angles. 60

Two rollers 6 and 7 are revolvably mounted in suitable bearings, in the jaws 4 and 5 and are designed for feeding the paper web F between them. These rollers are arranged in close proximity to each other as shown in 65 Fig. 2, being spaced apart sufficiently to permit the paper web F to pass between them and be fed thereby on a forward pull being exerted on said web. A spring catch 12 reliably connects the jaws 4 and 5 at their free 70 ends to hold the rollers in operative position. The upper jaws 4 have transverse slots 13 therein in which the spindle ends of the upper roller 6 are mounted to adapt said roller to move laterally relative to the roller 75 7 to provide for variation in thickness of the paper used. Plate springs 14 are mounted to bear on said spindle ends to hold the roller 6 in yieldable engagement with the roller 7. 80

The upper roller 6 has a peripheral recess 8 formed in one end thereof and extending around the entire circumference to receive a flexible element 9 which is adapted to be wound on said roller. This element 9 is 85 here shown in the form of a cord secured at one end to the cross bar D of the holder and at its other end in the recess 8 of the roller 6. In the other end of the roller 6 is mounted a spring controlled shaft 10 which 90 projects beyond the end of the roller and forms a journal for this end of the roller. A coiled spring 11 encircles said shaft 10 and is secured at one end to said shaft and at its other end to the roller as is shown clearly 95 in Fig. 6. The turning of the roller 6 in one direction will wind up the spring 11 and unwind the cord 9 from the roller which occurs when a pulling tension is exerted on the paper web F and when said web is released or torn off the spring will uncoil and thereby feed the web forward a short distance and at the same time will wind up the cord 9 on the roller 6 and raise the attachment into the position shown in Fig. 1 leaving the end of the web projecting a sufficient distance to be readily gripped when a further supply of paper is desired. 100 105

While I have described my invention with more or less minuteness as regards details and as being embodied in certain precise forms, I do not desire to be limited thereto 5 unduly any more than is pointed out in the claims. On the contrary, I contemplate all proper changes in form, construction and arrangement, the omission of immaterial elements and substitution of equivalents as 10 circumstances may suggest or render expedient.

I claim as my invention:

1. The combination of a pivoted turnable roll holder, arms pivoted out of line with 15 the roll holder axis, feed rolls upon the outer ends of said arms, one of said rolls containing a torsional spring, a cord coiled around said feed roll and having its other end fixed, said cord winding upon the feed 20 roll and advancing the paper when the feed roll holder is raised about its pivots.

2. The combination with a paper roll holder and its journal support, of arms journaled out of the axial line of the holder, 25 feed rolls and cutters mounted upon the outer end of the arms and between which the paper is advanced, a cord fixed at one end and having the opposite end coiled around one of the feed rolls, a torsional 30 spring within said roll adapted to wind the cord and advance the paper as the arms are moved up and down about their pivot.

3. The combination with a paper roll support, of a frame pivotally mounted on said 35 support, feed rollers mounted in said frame, a cutter disposed in advance of said rollers, a flexible element connected at one end to one of said rollers and at its other end to said roll support, and a spring carried by 40 said roller for winding up said flexible element when the roller is turned in one direction.

4. A feeding attachment for paper roll holders comprising a frame having revolu- 45 bly mounted rollers arranged therein and disposed adjacent to each other, a cutter arranged in advance of said rollers one of said rollers having a recess in one end, a shaft revolvably mounted in said recess and 50 projecting beyond said roller to form a journal for one end thereof, and a coiled spring wound on said shaft and connected at one end thereto and at its other end to said roller.

5. A feeding attachment for paper roll holders comprising a frame having revolu-

bly mounted rollers arranged therein and disposed adjacent to each other, severing means arranged in advance of said rollers one of said rollers having a recess in one end, a shaft revolvably mounted in said recess and projecting beyond said roller to form a journal for one end thereof, and a coiled spring wound on said shaft and connected at one end thereto and at its other end to said roller, the other end of said roller having an annular recess therein, and a flexible element secured at one end to said recessed end of said roller and adapted to be connected at its other end to a fixed sup- 70 port.

6. The combination with a paper roll support, of a feeding attachment comprising hingedly connected jaws having arms extending at right angles therefrom, the free 75 ends of said arms being pivotally mounted on said support, said jaws having cutter blades, a pair of rollers revolvably mounted adjacent the rear edge of said cutting blades and in close proximity to each other, one of 80 said rollers having a spring journal at one end and a flexible element connected with said roller and with said support.

7. The combination with a paper roll support, of a feeding attachment comprising 85 hingedly connected jaws having arms extending at right angles therefrom, the free ends of said arms being pivotally mounted on said support, said jaws having cutting blades, a pair of rollers revolvably mounted 90 adjacent the rear edge of said cutting blades and in close proximity to each other, one of said rollers being movable laterally relative to the other, and means for holding said rollers in yieldable engagement. 95

8. In a roll paper supply apparatus of the character described, a frame including arms pivoted out of line with the roll axis and tiltable with relation thereto, feed rolls and cutter blades carried upon said frame, one 100 of said rolls and blades being mounted upon a transversely hinged support, at one end, and provided with a yielding latching device at the other end.

In testimony whereof I have hereunto set 105 my hand in the presence of two subscribing witnesses.

CHARLIE EDWIN WEEKS.
